UNITED STATES PATENT OFFICE

WILLIAM J. HURST, OF MAQUOKETA, IOWA

DRAG HARROW CLEANER

Application filed September 5, 1929. Serial No. 390,530.

The present invention relates to a drag harrow and particularly to an attachment therefor which has for its prime object to provide means whereby the drag harrow 5 may be readily cleaned of any weeds, corn stalks, or any other object caught on the teeth thereof while in operation.

Another very important object of the invention resides in the provision of a cleaning device of this nature which saves time and labor, is easy to manipulate, simple in construction, inexpensive to manufacture, strong and durable, and thoroughly efficient and reliable in use and operation.

With the above and numerous other objects in view as will appear as the description proceeds, the invention resides in certain novel features of construction, and in the combination and arrangement of parts as 20 will be hereinafter more fully described and claimed.

In the drawings:

Figure 1 is a side elevation of the drag harrow showing my attachment mounted thereon,

Figure 2 is a similar view showing the harrow tilted and in longitudinal section,

Figure 3 is an enlarged detail sectional view through the attachment,

Figure 4 is a sectional view taken substantially on the line 4-4 of Figure 3,

Figure 5 is a sectional view taken substantially on the line 5-5 of Figure 3,

Figure 6 is a perspective view of the lower 35 end of the lever, and

Figure 7 is a sectional view taken substantially on the line 7-7 of Figure 3.

Referring to the drawing in detail it will be seen that the numeral 5 denotes a well known form of drag harrow including among other elements a center transverse shaft 6.

A bushing 7 formed in sections is disposed circumjacent the shaft 6 by means of bolts 8 engaged in ears 9 and at one end has a lug 45 10 rising therefrom in which the lower end of a lever 11 is pivoted by means of pin 12.

A sectional hub 14 is disposed circumjacent the bushing 7 to rock thereon being mounted by means of bolts 15 extending through ears

50 16 and this hub 14 has oppositely radiating

arms 17 terminating in ground engaging teeth 18. An annular ratchet member 19 is formed in sections and fixed to the hub 14 by means of bolts 20 or in any other suitable manner.

A lug 21 extends from the lever 11 and has a pin 22 slidable therethrough on the lower end of which is a pawl 23 cooperatable with the ratchet 19 by means of spring 24 pressing the pawl in engagement with the ratchet.

This pawl is slidable through an ear 25 projecting from the lever 11. An operating rod 26 is engaged with the upper end of the lever and extends through a guide eye 27 on the lever 28 of the harrow.

A cable 30 is attached to the upper end of the lever 11 and extends forwardly under a guide pulley 31 mounted in brackets 32 rising from the front end of the harrow. A spring 33 is engaged with the frame of the harrow and the lever 11 to normally hold the lever 11 in the position shown in Figure 1.

When it is desired to clean the teeth of the harrow and the harrow is moving forwardly, the lever 11 is rocked forwardly by pushing forwardly on the rod 26 or pulling forwardly on the cable 30 thereby rocking the lever 11 and causing similar rocking movement of the ratchet 19, and the hub 14 thereby swinging one of the arms 17 downwardly to engage its foot 18 with the ground as is indicated in dotted lines in Figure 1 thereby raising the forward end of the harrow and allowing any objects on the front or forward teeth of the harrow to drop therefrom.

As soon as the rod 26 or cable 30 is released the spring 33 returns the lever 11 to its initial position. With the harrow in the position shown in dotted lines in Figure 1 it will be seen that as it is pulled forwardly it will then rock to the position shown in Figure 2, so as to allow objects to drop from the rearward teeth of the harrow and then as the harrow pulls forwardly the arms will swing around, the ratchet having its teeth passing by the pawl as will be readily appreciated until the harrow is back again in the position shown in Figure 1.

It is thought that the construction, opera-

tion, utility and advantages of this invention will now be quite apparent to those skilled in this art without a more detailed description thereof.

5 The advantage of this draw harrow cleaner is that it saves time and labor as in dragging, the operator has to lift the drag up by hand and clean it whereas with this cleaner he does not have to stop his team or tractor but just pull the rope or push the rod

10 and the team or tractor does the work.

This attachment is made in parts so that it can be put on any draw harrow without taking the harrow apart.

15 The present embodiment of the invention, of course, has been described in considerable detail merely for the purposes of exemplification since in actual practice it attains the features of advantage enumerated as desirable in the statement of the invention and

20 the above description.

It is apparent that changes in the details of construction, and in the combination and arrangement of parts may be resorted to without departing from the spirit or scope of

25 the invention as hereinafter claimed or sacrificing any of its advantages.

Having thus described my invention, what I claim as new is:

30 1. In a drag harrow of the class described including a shaft, a hub rockable on the shaft, arms extending from the hub, a ratchet on the hub, a lever, means for rockably mounting the lever, a spring pressed pawl in the lever engageable with the ratchet, said arms terminating in ground engaging teeth, a spring for holding the lever in a normal predetermined position.

35 2. In a drag harrow of the class described including a shaft, a hub rockable on the shaft, arms extending from the hub, a ratchet on the hub, a lever, means for rockably mounting the lever, a spring pressed pawl in the lever engageable with the ratchet, said arms terminating in ground engaging teeth, a spring for holding the lever in a normal predetermined position, remote control means for the lever.

40 3. A cleaner for drag harrows comprising, in combination a drag harrow including a shaft, a bushing on said shaft having a lug at one end, a hub rockable on the said bushing and having arms extending radially therefrom, said arms terminating in ground

45 engaging teeth, the ratchet on the said hub, a lever pivoted to the lug of said bushing, a spring tensioned pawl carried by the lever and engageable with the said ratchet, means for operating the lever to rotate the said hub

50 for disposing an arm thereof in contact with the ground, and lever tensioning means for returning the said lever to normal position upon release of the lever operating means.

In testimony whereof I affix my signature.

WILLIAM J. HURST.
